TUBE EXTRUDING DIE AND METHOD

Harold F. Temple, Freeport, N. Y., assignor to
 Victor Metal Products Corporation, Brooklyn,
 N. Y., a corporation of New York

Application November 27, 1939, Serial No. 3063319

13 Claims. (Cl. 207—6)

1 This invention relates to impact extrusion apparatus and processes whereby thin walled hollow articles are formed from a disc of extrudable metal by means of a sudden pressure or blow or, in other words, by impact extrusion.

Thin walled cylindrical tubes such as collapsible tubes for the reception of pasty material have heretofore been made by the impact extrusion method wherein a disc or slug of non-ferrous extrudable metal such as tin, aluminium, lead, zinc or alloys thereof have been suddenly pressed or struck with a vertically reciprocating plunger or male die after the disc has been inserted in a suitably shaped female die. The excess metal of the slug is thus caused to bow suddenly upwardly out of the female die and around the plunger. Its cylindrical shape is determined by the cylindrical shape of the opening of the female die and the cylindrical shape of the lower end of the male die or plunger. The thickness of the tube wall is determined by the difference between the diameters of the die and the plunger. The shape of the tube bottom may be greatly varied being entirely die-formed within the female die by the pressure of the lower end of the male die or plunger as contrasted with the formation of the remainder or body of the tube by extrusion.

Insofar as I am aware, no attempt has heretofore been made, other than shaping the female die, to control or interfere with the bow of the metal out of the female die during the extremely small interval of time during which the impact extrusion operation takes place. The shape of the resulting tube has therefore been determined heretofore solely by the shape of the opening in the female die and the corresponding slightly smaller shape of the cooperating extreme or lowermost end of the plunger.

I have found, however, that after the metal flows upwardly out of the female die to begin the formation of a tube, the direction of the flow of the metal may be controlled and varied to a substantial extent, limited only by the ductility of the metal used whereby it becomes possible to greatly vary the shape of the extruded part or body of the resulting tube from the cylindrical shape heretofore in general use. It also becomes possible to change the diameters of selected parts of the length of the resulting tube by diverting the metal flowing along the plunger into a different direction and it further becomes possible to change the cross-sectional shape and size of the tube at various parts of its length. Furthermore, by changing the shape of the cooperating parts of the die, the shape of the bottom part of the tube

may also be greatly varied and the tube provided with lugs, openings, necks, embossing or the like as in ordinary die pressing operations, the extruded tube part or body being formed together with its die-pressed part all in a single operation and from a suitable slug or disc.

My invention therefore contemplates the provision of a method of controlling and diverting the metal flowing out of a female die during an impact extrusion operation whereby tubes, cans, shells and the like of multiple diameter and of varied cross-sectional shapes and of any suitable inner and outer configuration at its die-pressed lower end may be formed in a single operation and from an extrudable slug.

My invention further contemplates the provision of simple and efficient means for controlling and diverting the metal flowing out of a female die during an impact extrusion operation for producing the hollow articles above mentioned.

My invention further contemplates the provision of a sleeve of predetermined shape and size adapted to be readily adjusted and held in place on the plunger or male die of an extruding press for controlling and diverting the metal flowing out of the female die thereby to produce thin walled hollow articles varying in diameter at different parts of their lengths and also varying in the cross-sectional shape thereof.

30 The various objects of the invention will be clear from the description which follows and from the drawings in which,

Fig. 1 is a vertical section of a pair of impact extrusion dies to which my invention has been applied.

Fig. 2 is a partial section and front elevation of the same in the position wherein the extruding operation has been completed to form a tube having different multiple diameters.

40 Fig. 3 is an elevational view partly in section of supplementary means for performing a typical trimming and forming operation upon a can or tube extruded in accordance with my invention and for the purpose of finishing the tube or can.

45 Fig. 4 is a fragmentary vertical section of a modified form of the dies employed for the purpose of forming an open end tube, can or shell.

Fig. 5 is a top plan view of a modified form of 50 the plunger or male die employed for the purpose of extruding tubes, cans or shells with a beaded wall surface for part of its length.

Fig. 6 is a similar view of another modified form of the male die or plunger employed for the purpose of extruding hollow articles having part

of the length thereof expanded into hexagonal form.

Fig. 7 is a similar view of the same showing the means employed for extruding a hollow article in which the lower cylindrical part is expanded into an upper hexagonal part and in which the lower end part of the article is die-formed into any desired shape such as conical.

Fig. 8 is a similar view of the dies showing the means employed for extruding a hollow article in part hexagonal in cross-section and in part circular in cross-section.

In the practical embodiment of the invention shown by way of example, the male die 10 is substantially of the usual construction being provided with the passage 11 for compressed air which is intended to operate the air valve 12 to discharge the article extruded upon the plunger or male die. In the form of the invention shown, the male die 10 is of the usual cylindrical shape and is reciprocated by suitable means well known in the art to enter and to leave the female die 13 and to compress the slug 17 therein. The die cavity 14 of said female die is, as is customary, also of generally cylindrical shape but in this case is provided with a substantially closed bottom wall 15 for the production of tubes, cans, shells, casings, or the like hollow articles having a closed bottom as 16 (Fig. 2). The slug or disc 17 is inserted into the female die by mechanism well known in the art after which the plunger is moved down with considerable force against the slug thus compressing the slug within the die cavity. The lower end 18 of the plunger cooperates with the wall of the die cavity to form the lower end of the tube into the exact inner and outer shapes desired while at the same time, the excess material is suddenly forced out of the die cavity and squirts or flows upwardly therefrom around the plunger to form a thin-walled tube, having in the instance now being described, a closed bottom.

It will be understood, however, that the shape of the tube bottom may be varied as desired depending upon the shape of the lower end 18 of the plunger and the shape of the bottom portion of the die cavity. For example, in Fig. 7, I have shown the lower part of the wall 19 of the die cavity as being in the shape of a frustum of a cone and the end part 20 of the male die as correspondingly shaped.

In Fig. 4, the male die is provided with a projection 21 of the desired diameter which projection is intended to enter the opening 22 communicating with the die cavity and thereby to form a readily severable portion 23 which when later cut off leaves the bottom of the tube 24 completely or partly open as desired. Other desired forms of the lower die-formed end portion of the resulting tube may be readily produced merely by varying the shape of the die cavity and the shape of the lower end of the plunger as will now be readily understood and need not be further described.

However, an important feature of the invention is the diversion, expansion and control of that portion of the metal of the slug 17 which flows upwardly out of the die cavity and around the plunger 10. By so controlling and diverting the upwardly flowing metal within the limits of the ductility of the metal, a great variety of sizes and shapes on different portions of the lengths of the resulting tube may be produced. In the form of the invention shown in Figs. 1 and 2, I prefer to control and divert the upwardly flowing excess metal by means of a suitable sleeve

as 25 adjustably secured to the plunger 10 at any point of the length of said plunger as by means of one or more set screws 26. By adjusting the position of the sleeve vertically, the relative lengths of the expanded and unaltered portions of the tube are determined. The sleeve 25 is slidably and closely fitted to the plunger and may take a variety of different forms. In the form shown, the lower cylindrical portion 27 of the sleeve terminates in a lowermost bevelled or conical edge portion 29. At its upper end, the sleeve is enlarged as at 28 to provide enough material for the proper operation of the securing means.

It will be understood, however, that if desired, the sleeve may be formed integrally with the plunger. I prefer to make the sleeve separate for purposes of economy, since the same plunger may be used with sleeves of different sizes or shapes and each sleeve may be adjusted vertically when it is desired to change the relative lengths of the different tube portions.

As shown in Fig. 2, the metal flowing out of the die cavity is first given the smaller cylindrical shape determined by the lower end portion 18 of the plunger and the shape of the die opening 13 and flows in a predetermined vertical path but when said metal reaches the bevelled part or shoulder 28 of the sleeve, it is diverted from its normal path of flow and forced to move along said bevelled edge and in a different path thereby expanding the diameter of the upper path of the tube thus formed to the diameter of the portion 27. Since the metal resists expansion after it reaches the upper corner 29 of the bevelled portion, the inherent tension therein resisting expansion causes the metal to change its direction of flow again and to hug the wall 27 thereby producing the enlarged cylindrical portion 31 on the upper part of the tube.

It will thus be seen that by a single extruding operation and by the use of the sleeve 25 or of a correspondingly shaped plunger, it becomes possible to extrude in a single operation a tube having two different diameters at different portions of its length. That is, the lower portion 32 of the tube may be made cylindrical and of a given smaller diameter while the upper portion 31 of the tube may also be made cylindrical and of a larger diameter, said portions being joined by the conical portion 33. After the plunger has been raised out of the female die, the resulting thin-walled hollow article is discharged from the plunger by the air blast through the passage 11.

The thus extruded tube may be readily finished on another machine by trimming it to the proper length and forming the portion 33 into the exact right-angled shape desired. An additional operation such as threading or the like may also be performed in a manner and by means well known in the art. For example, in Fig. 3, I have shown the trimming and forming roller 35 provided with the trimming tool 36 for cutting the tube to the required length and also provided with the forming tool 37 for accurately forming the corner portion 38 to the exact shape desired while the tube is mounted on the suitable revolving mandrel 39.

It will be understood that the method hereinbefore described, that is, the extrusion of a tube having different diameters from a slug in a single operation is not limited to the formation of cylindrical portions on the tube but numerous other shapes may be given to the tube. For example, in Fig. 5, I have shown the male die 10 provided with a sleeve 40 having a beaded exterior surface 41 to replace the cylindrical surface 27. I have

found that the flowing or extruded excess metal owing to its internal tension hugs the surface 41 and produces a correspondingly beaded upper portion on the tube and does not continue flowing in the direction of the inclined shoulder 28.

In Fig. 6, I have shown the cylindrical portion 27 of the sleeve replaced by the hexagonal portion 42 thereby to produce a thin-walled upper portion on the tube hexagonal in cross-section and slightly larger if desired than the cylindrical portion 32 of the tube.

Other modifications of the formation of the walls of the sleeve will be obvious in connection with the formation of terminal edge portions on the extruded tube of other shapes and designs. It will also be understood that by making the beads 41 concave instead of convex, a fluted upper end will be obtained on the tube in a manner which will now be obvious.

Nor is my invention limited to the formation of cylindrical lower portions on the tube. For example, in Fig. 8, I have shown the lower end 50 of the male die of hexagonal cross-section, the die cavity 51 being correspondingly made of hexagonal cross-section. The sleeve 52, however, has been made cylindrical. Consequently, when the tube is extruded, the lower portion 53 thereof is of hexagonal cross-section determined by the lower portion of the plunger while the upper portion 54 of the tube is of circular cross-section and cylindrical as determined by the shape of the sleeve 52.

As shown in Fig. 7, the lower portion 55 of the tube is cylindrical while the upper portion 56 thereof is of hexagonal cross-section as determined by the hexagonal shape of the sleeve 57 which is similar to the sleeve 42. The die-formed lower end of the tube is here shown as conical for purposes of illustration.

It will now be understood that by varying the shape of the surface of the sleeve, any required shape and diameter within the limits of ductility of the metal may be produced. That is, any pyramidal or prismatic tube of regular or irregular polygonal cross-section may be produced as well as any cylindrical tube of regular or irregular curved cross-sectional shape. When the sleeve surface is made eccentric to the surface of the plunger, eccentric upper parts may be correspondingly produced on the extruded tube. The lengths of the extruded lower portion 32 and of the upper portion 31 may readily be controlled and determined by shifting the sleeve 25 vertically in the proper direction on the plunger. It will further be understood that by the use of additional shoulders or bevelled portions 28 on the sleeve, and additional surfaces of the diameters different from the surface 27, tubes having multiple or more than two different diameters and in fact any number of different diameters within the limits of expansibility of the metal can be produced. I have found, however, that the shoulders connecting the different surfaces of the sleeve and leading from the lateral surface of the plunger to that of the sleeve should be arranged preferably at an obtuse angle to the adjacent surfaces between which they are arranged so as to change the direction of flow of the metal with as little abruptness as possible unless a flared, beaded, curled or serrated edge is desired. By enlarging or reducing the diameter of the portion 21 of the male die (Fig. 4) or plunger, casings, shells or tubes having completely open ends may be produced, the tube being finished by a knock-out operation on the weakened lower end thereof.

It will be understood that the term "tube" as used herein is intended to include any comparatively thin-walled hollow article regardless of its shape and the number of different diameters therein or whether one end is closed or open, or whether said end is provided with a neck or a thickened portion or with lugs or projections of various sorts and types for different purposes.

It will thus be seen that I have provided a simple but commercially practical method for extruding in one operation from a slug a multiple diameter tube having any regular or irregular polygonal or curved perimeter and having any desired type of edge such as curled, flared, serrated and the like and having any type of die-formed open or closed end thereon.

It will also be seen that I have provided simple but efficient means for carrying out the method described herein and further that I have provided a new tube formed in one operation from a slug and of multiple diameter and/or of different cross-sectional shapes.

While I have shown and described certain specific embodiments of my invention, I do not wish to be understood as limiting myself thereto, but intend to claim the invention as broadly as may be permitted by the state of the prior art and the scope of the appended claims.

Claim:

1. An apparatus for the impact extrusion of hollow soft metal articles in one operation and including a plunger having an end portion adapted to enter into and cooperate with a female die and a remaining portion at all times arranged beyond the female die, means for controlling and diverting metal flowing out of the female die in solid form axially along the plunger at high speed under high axial pressure and in a formative state from the normal direction imparted thereto by the plunger and the die, said means comprising a sleeve surrounding said remaining portion of the plunger and adjustably mounted thereon.

2. In apparatus for extruding hollow articles from a metal slug in one operation, a plunger having an end portion adapted to enter and to cooperate with a shallow female die to form one end part of an article, a sleeve on the remaining portion of the plunger substantially instantaneously to divert that part of the metal of the slug flowing past said end portion of the plunger at high speed and in a formative state, and means for adjustably securing the sleeve to the plunger.

3. The method of producing a one-piece tube having a lower die-formed part, a first body part of a first predetermined uniform cross section, a second body part having a second predetermined uniform cross section different from the first cross section and a substantially conical part joining the first and second body parts, said body parts having thin walls of a thickness approximating the thickness of the walls of conventional collapsible metal tubes and conventional cans of corresponding diameter, said method comprising placing wholly within a female die an unheated non-ferrous disc slug of metal extrudable at room temperature with the upper surface of the slug below the top of the die thereby to leave at least the upper part of the die empty of slug metal, striking the slug a single rapid blow by rapidly moving a punch into the die first to initiate the die-forming of the slug into the die-formed part of the tube by the downward pressure of the punch on the slug before any extrusion of slug metal out of the die occurs, thereby to move part

of the slug metal into position to fill the empty space between the punch and the die, second to extrude the excess part of the slug metal thus moved out of the die, by moving said metal in a first straight line path, said path being of substantial length corresponding to the length of said first body part and being parallel to the direction of movement of the punch, while continuing the die-forming of part of the slug within the die until just prior to the final downward movement of the punch, and finally completing the die-forming operation while simultaneously completing the extrusion of the remaining excess of slug metal out of the die and also simultaneously stretching a predetermined length of the upper part of the tube by moving said length through an angular relatively short path non-parallel to said first straight line path, thereby radially stretching successive parts of said predetermined length first to a substantially conical shape corresponding to the shape of said substantially conical part of the tube and then to said second predetermined cross section as the various parts of said predetermined length move past a given portion of the punch, the metal moving in a straight line path parallel to and spaced outwardly of the first straight line path free of radial stress after the metal passes said portion of the punch.

4. The impact extrusion method of producing a two-diameter thin-walled elongated metal tube by the action of an extrusion punch and die upon an unheated disc slug of extrudable metal placed entirely within the die, said tube having a die-formed lower end part, an extruded upper end part of uniform circular cross section and an extruded intermediate part of a smaller uniform circular cross section, said method comprising forming the end die-formed part of the tube between the die and the punch, forming the intermediate part of the tube solely by extrusion of the slug out of the die and axially along the punch, and forming the upper part of the tube by continuing the extrusion of the slug along the punch combined with radial stretching of the upper part of the tube within the limits of the ductility of the metal as the various portions of said upper part move first obliquely past a predetermined part of the punch and then freely axially of the punch.

5. The method of producing a thin-walled elongated tube having a die-formed lower end part, an extruded upper end part of uniform cross section, and an extruded intermediate part of a uniform cross section different from that of the upper end part, said method comprising placing an unheated slug of non-ferrous metal extrudable at room temperatures wholly within a die with the upper surface of the slug below the top of the die, moving a punch downwardly into a cooperating die and then into the slug a distance less than the depth of the die, and, during the initial part of the movement of the punch into the slug initiating the die-forming of the end part of the tube by the downward pressure of the punch on the slug before any extrusion of the slug metal out of the die occurs, continuing the die-forming of the lower end part of the tube and simultaneously extruding the slug metal in excess of the die-formed part of the tube axially of and around the punch and out of the die along an initial path of substantial length to form the intermediate part of the tube partly within and partly above the die, stretching the leading end part of the metal extruded out of the die along a predetermined portion of the upper end of said initial path in substantial upward spaced relation to the

die at all times to divert the flowing metal progressively into an angular path non-parallel to the initial path, and freeing the flowing metal at the uppermost end of said angular path from stretching stresses thereby to permit the uppermost part of the metal to flow in a final path parallel to the initial path and to assume the stretched shape of the upper part of the tube permanently and progressively along said upper part until downward movement of the punch ceases.

5. The impact extrusion method of producing a thin-walled elongated tube having a die-formed end part, an extruded and stretched upper end part of a first uniform cross section and an extruded intermediate part of a different uniform cross section, said method comprising initiating the die-forming of an unheated non-ferrous slug at room temperatures by impact extrusion at high speed, completing the die-forming while simultaneously extruding the slug into a tube of uniform cross section corresponding to said different cross section while the tube is being lengthened during the extrusion operation, and continuously stretching the upper part of the tube progressively and uniformly to said first cross section by interposing an obstruction in a relatively short length of the path of the slug metal at a selected point below the end of the path of the leading end edge of the extruded metal and at the upper end of the path of the intermediate extruded and unstretched part of the tube.

6. The impact extrusion method of producing a thin-walled tube having a die-formed part, a first body part having a predetermined uniform cross section, and a second body part having a second and different predetermined uniform cross section, said method comprising the performance of a simultaneous die-forming, extruding and radial stretching operation upon an unheated disc-like slug of extrudable non-ferrous metal placed wholly within the die to form the metal first to leave the die into a tube part corresponding in cross section to said predetermined cross section and, while said metal moves past a predetermined part of the punch which is at all times in upward spaced relation to the die, expanding the tube part to said second cross section.

7. The impact extrusion method of claim 7 wherein one of the body parts of the tube is of circular cross section and the other body part is of polygonal cross section.

8. The impact extrusion method of claim 7 wherein one of the body parts of the tube is of circular cross section and the other body part is of polygonal cross section.

9. The method of producing a tube having relatively thin walls of the thickness approximately of conventional cans and shells of the same diameter as the tube and having one wholly extruded portion thereof of a uniform cross sectional shape different from that of another wholly extruded portion of the tube, said method comprising producing the tube from an unheated shallow disc slug of non-ferrous extrudable metal by impact extrusion in a single operation by first placing the slug wholly within an impact extrusion die and then striking the slug a blow with an impact extrusion punch to cause the metal of the slug to flow in a straight line path in a given direction along the punch for a sufficient distance to form the first mentioned portion, and diverting and controlling the flow of the leading portion of the extruded metal from the given direction by the punch to an angular direction for a predetermined relatively short path to stretch said leading portion within the

limit of ductility of the unheated metal, and finally to a straight line path parallel to and spaced outwardly and upwardly of the first mentioned straight line path during the extrusion flow of the metal to form said second mentioned portion.

10. In the impact extrusion method of making a thin-walled elongated tube wherein the metal of a cold slug wholly within and below the top of a die is extruded by causing the metal to flow out of the die along a path of substantial length in a vertical direction, the step of changing the direction of flow of that part of the metal first to leave the die from the vertical direction to an inclined direction through a 15 relatively short path after said part has flowed in the given direction for a sufficient distance to form the greater part of the length of the tube, said step stretching the metal first to leave the die progressively as said metal passes a given point and then releasing the metal from stress past said point to permit the metal to flow again vertically to form an upper tube part of predetermined uniform cross sectional shape.

11. In the impact extrusion method of making a tube from an unheated slug wholly within a die and of insufficient size to fill the die, in one operation, the step of first initiating the die-forming of one end part of the tube by spreading the slug to fill the die and, during the progress of the die-forming operation, axially extruding excess slug metal out of the die to form progressively a substantial length of an intermediate part of the tube, progressively expanding the other end part of the tube as said other end part moves past a given point, and releasing said other part from radial stress after it has passed said point.

12. In the impact extrusion method of making a thin-walled elongated hollow article from an unheated shallow disc-like slug of cold extrudable metal in one operation, die-forming one end part of the article while the slug is wholly within a die and, while extruding the slug

to form the thickness of the remainder of the article to approximately the least thickness permitted by the speed of the operation and the ductility of the metal, expanding the other end part of the article as the metal thereof passes a given point during the extruding operation by interposing an obstruction of predetermined shape in the path of flow of the thinned extruded metal at said point to divert the flow to a different relatively short path thereby to stretch said other end part within the limit of ductility of the metal, and releasing said other end part of all radial stress thereon after it has passed the obstruction.

13. The method of claim 11 and after the outermost portion of said other end part has moved a predetermined distance free of stress, expanding a predetermined portion of said other end part a second time in substantially the same 20 manner as said portion was first expanded.
